DESIGN FOR AN EGG BOILING RACK

Solomon Rapport, New York, N. Y.

Application August 21, 1945, Serial No. 121,537

Term of patent 7 years

(Cl. D44—24)

To all whom it may concern:

Be it known that I, Solomon Rapport, a citizen of the United States of America, and residing at New York city, in the county of the Bronx and State of New York, have invented a new, original, and ornamental Design for an Egg Boiling Rack, of which the following is a specification, reference being had to the accompanying drawing, forming a part thereof.

Fig. 1 is an elevation of an egg boiling rack, showing my new design.

Fig. 2 is a top plan view thereof.

The dominant feature of the design resides in the portions shown in full lines.

I claim:

The ornamental design for an egg boiling rack, substantially as shown and described.

SOLOMON RAPPORT.
